COKE OVEN WITH INTERNALLY HEATED
HEATING WALLS

Franz Puening, Essen, Germany

Application October 3, 1935, Serial No. 43,341
In Germany November 7, 1934

5 Claims. (Cl. 202--105)

The invention relates to coke ovens especially for low temperature coking, in which movable internally heated hollow heating walls are employed.

5 Certain constructions of this type have already become known in which the movable heating walls are enclosed by a housing. In these cases the hangers for the individual walls as well as the conduits for supplying the heating gases from 10 the source of heat, which is arranged outside of the enclosure, penetrate the walls of the enclosure.

This arrangement shows several disadvantages, of which the essential ones are, that the unnecessary void spaces in the enclosure have not 15 yet become reduced sufficiently, that the points of connection between the hanging rods and the heating walls inside of the enclosure as well as the spreading mechanism, require expensive constructions, that the accessibility of the heating walls is unsatisfactory, that the conduits for heating gas and the equipment comprising the source 20 of heat are in need of a decided reduction of outside dimensions, so that through a reduction 25 of cost of investment the whole plant becomes economically more successful. This is especially important if the low temperature coking plant has only a small capacity, as for instance in case of small gas plants, in which several small independent units are required, each of which may 30 have a capacity of only 1 ton of coal per day.

In order to overcome these disadvantages, the invention provides that a portion of the surface of the enclosure surrounding the heating walls, 35 is replaced and formed by surfaces, which belong to the outer surfaces of the heating walls. One of the results, of this arrangement among others is especially useful and consists in the possibility, of supplying new heat to the combustion gases, 40 circulating inside of the individual movable heating walls either wholly or partly by means of burners, arranged inside of the heating walls, and this possibility helps to overcome a number of the other disadvantages, mentioned before.

45 The drawings show two embodiments of the invention.

Fig. 1 shows a sectional elevation of a heating wall and the means for its suspension and the fan for recirculating heating gas.

50 Fig. 2 shows a plan view of the same arrangement.

Fig. 3 shows a sectional elevation of 3 heating walls with the means for suspending and moving the walls.

55 Fig. 4 shows a sectional elevation through a

different embodiment of the invention without a fan.

Several of the iron hollow heating walls 1 (Fig. 1) are suspended alongside of each other and form between them the coal chambers 2 5 (Fig. 2). They are enclosed by an enclosure 3 of refractory material, which at its lower end comprises a removable bottom door 4 and at its upper end an opening 5, which is closed by the upper portions of the heating walls. Each heating wall 1 is suspended by means of hanging rods 6 (Fig. 1) from an iron structure 7, which supports the oven structure, the hanging rods connecting to the heating walls by means of brackets 8, which penetrate the layers of insulating 10 material 9, with which the upper surfaces of the heating walls are covered.

The interior of the heating walls is divided through partition walls 11, 12 into a system of heating flues which communicate with the main 20 heating gas flues 16 and 17 the latter being in common for all heating walls. For this communication the first and last heating flues of each wall are equipped with openings 13 while main heating gas flues 16 and 17 have corresponding openings 14. The upper rims of all openings 13 and 14 have the shape of annular cups. Gastight connections between the openings 13 and 14 are established by return elbows 15. Each of these return elbows has its 2 open 30 ends turned downward. They enter the annular cups of the openings 13 and 14 and rest in them and are sealed in them by means of lead seals or the like. The annular cups are shown to be of ample size, so that the elbows are permitted a 35 certain amount of movement inside of the cups with the result that whenever the heating walls are spread apart for the purpose of coke discharge, the return elbows follow the motion of the walls, executing essentially a rotating and to 40 a minor degree also a sliding motion in the cups.

A fan 24 is provided for the re-circulation of combustion gases through the interior of each heating wall. This fan discharges the combustion gases into the common pressure room 23 45 from where they flow through opening 18, the main flue 16 and the return-elbows 15 and the elbows 13 down and up through each heating wall, as indicated by the arrows, finally leaving at the lefthand through other elbows 13, return 50 elbows 15, main flue 17, return flue 19, opening 21 finally entering the suction flue of fan 24. Two damper plates 30 and 40 are provided, which are supported by steel rods, of which only the centre lines are indicated. When these damper 55

plates are hoisted simultaneously by means of the steel rods, the openings 18 and 21 will be closed, while the openings 10 and 20, which were previously closed, will become free with the result 5 that the combustion gases delivered by fan 24 into pressure room 23 will thereafter flow through the heating walls in the opposite direction, first entering through opening 20 into flues 19 and 17, and returning to the fan through flue 16 and opening 10 and suction flue 22. In the preferred 10 manner of operation it is intended to change the position of the two damper plates periodically, for instance every 10 minutes, from their low position indicated in the drawings to the high 15 position in front of openings 18 and 21 and back again to their low position. In this manner a reversal of the flow of the combustion gases through the heating walls and all connecting flues and return elbows is obtained, thus guarding 20 them against uneven heating.

Burner 25 protrudes into pressure room 23 and burners 26 protrude into the connecting spaces above the partition walls 12. These burners 26 receive their supply of combustible gases through 25 pipes 21, which are connected to the main supply lines for combustible gas 29 by means of flexible connections 28, which permit the motion of the heating walls. The upper enclosing wall surfaces of the individual heating walls 1, are equipped 30 with closable openings 31, through which a torch for ignition may be introduced. A similar opening 32 has been provided for burner 25. The upper parts of the partition walls 12 are protected 35 against the direct action of the burner flames by means of insulating shields 33. The same protection can be obtained by installation of a fireproof shield 34, which has been indicated below the burner on the left hand of Fig. 1.

Fan 24, which together with the reversing 10 valves 30 and 40 and the burner 25 serves a battery of several heating walls 1, as a result of the indicated position of the valves 30 and 40 creates 15 contained in the heating flues a circulation of the heating gases as indicated by the arrows in Fig. 1.

The heat required by each heating wall is produced by burners 26 and the common burner 25. The surplus heating gases are conducted into the open or to heat recovery apparatus, through a chimney 35, which connects to the pressure room 23, in which the recirculated gases from fan 24 are divided into two parts, one flowing into stack 35, while the other flows past burner 25, carrying with it in the direction toward opening 18 and main flue 16 the fresh heating gases issuing from 15 the burner.

In the upper part of each burner screw-shaped guiding plates 36 have been provided, which impart a strong rotation to the entering fuel mixture, so that the mixture passes down on the inside of the combustion cone in rapid rotation. Thus a rapid uniform and quiet combustion of the fuel mixture is obtained, so that the colder gases coming from the fan are unable to disturb the process of combustion. For the same purpose, the combustion cones 37 also protrude a certain distance into the heating wall, so that one part of the recirculated heating gases passes beneath the burner mouth, while another part passes above the same.

The raw coal gases, which are produced by the distillation collect in the spaces between the heating walls above the coal charge, the height of which is indicated by line 38. For the lateral confinement of the coal in the coal chambers,

two small side chambers 39 (Fig. 2) have been provided, which are filled with coke breeze as is already known and described for instance in my U. S. Patent 1,916,331.

In each space 2 above the coal the raw coal 5 gases are conducted to the left (see arrow 41) and pass through the intermediate spaces between the elbows 15 and through connecting pipes 42 from the enclosure 1 into the collecting main 43. In those portions 44 of the roof lying 10 above the elbows 15, special covers 45 have been provided, which are heat insulated, and permit easy access to the elbows 15.

After the charging operation has been completed, the coal chambers 2 arranged between 15 the heating walls are closed during the coking operation by means of covers 46 (Figs. 2 and 3), which rest upon inclined edges of the heating walls and may be sealed airtight by a luting material like clay. A small gap 47 has been provided 20 between the side portions 44 of the roof and the uppermost portions of the heating walls, this gap permitting the motion of the walls, their heat expansion and the exact adjustment of their position. This gap is also made gastight 25 during coking operation for instance through a filler of clay 47. In order to facilitate the spreading apart of the walls 1 for the purpose of emptying the coal chambers 2, the brackets 8 (Figs. 1 and 3) are equipped with handles 50, to which 30 the operator may connect a pulling hook 60, which in case of light walls he may operate by hand or which he may connect to a mechanical pulling mechanism, already known and for instance described in my Patents 1,996,649, 1,996,651 35 and 1,916,331.

It is evident, that the coke oven described is considerably simplified in comparison to the older structures by virtue of the fact, that the entire roof construction, which in the known structures 40 is provided above the heating walls, has been omitted. This roof has been replaced by the upper portions of the heating walls and by the covers 46, which rest directly upon the edges of the heating walls. Furthermore an easy access 45 to the coke chambers and to the inside of the heating walls has been provided. The facility to observe the coke chambers and the inside of the heating walls is not interfered with by a great distance from the observer and by clouds of tar 50 vapours neither is the accessibility interfered with by virtue of a roof construction regardless of how great the spreading motion is of the walls. This is especially important for emptying the chambers in cases where coke of special form 55 shall be produced, for which purpose the walls are equipped on their outside with vertical ribs, so that the coke must be pushed out of the spaces between the ribs.

Furthermore it is now possible to connect the 60 hanging rods directly to the heating walls more especially to those parts of them, which are not surrounded by hot coal gases and which therefore have a higher wearing strength. The joints of the hanging rods are therefore always visible 65 and accessible for lubrication and for this reason and by keeping coal gases and dust away their abrasion is reduced to a minimum.

As can be seen from the drawings it is now 70 possible for the spreading mechanism to connect directly to the heating walls, thus obtaining essential structural simplifications, while in the older arrangements the spreading mechanism could be brought into contact with the walls only after the opening of the bottom door 4 and 75

the moving of the spreading mechanism, into position by means of the coke car. Previously the hinge points of the heating walls, as for instance shown in my American Patent 1,996,651 5 were located below the roof of the enclosure 3 next to the upper end of the heating walls. When spreading these walls apart a wedge-shaped space was created between the walls, which was wide at the lower but very narrow 10 at the upper end of the coking chamber. This space at the top of the coke chamber was insufficient and hampered the discharge of the coke especially in cases where the walls were equipped with ribs. In the new oven this fault has been 15 overcome, because the hinge-points around which the spreading motion of the walls takes place, now lie not below the cover but far above the heating walls at the uppermost end of hanging rods 6 so that upon spreading the heating walls 20 apart the width of each coking chamber is not only considerably increased at its lower but also at its upper end. Furthermore, if two hinge-points are employed in each hanging rod 6, as shown in Fig. 1, one at its upper and one at its 25 lower end, a wall when moved sideways will hang down vertically and the increments in width of the coking chamber will be uniform at the top and at the bottom of the coking walls, thus facilitating the coke pushing operation, especially 30 in case the walls are equipped with ribs between which the coke tends to adhere.

By doing away with the gas spaces between the heating walls and the roof the detrimental spaces, which cause a long exposure of the sensitive coal gases to the hot surfaces of the heating walls and the connecting gas ducts, are considerably diminished. The amount of recirculated heating gases has been reduced to a fraction of the former quantity by locating the source 35 of heat for the recirculated gases entirely or partly in the interior of the heating walls. In the present embodiment this amount is only about one quarter of that quantity, which would be required if the source of heat were placed 40 entirely outside of the heating walls. By increasing the number of the burners inside of the walls, the proportion of recirculated gases can still further be reduced.

The important reduction of recirculated heating gas makes it possible not only to select a 45 fan of much smaller capacity, but also to reduce the cross-sectional areas of the heating flues and gas passages, thus obtaining an important saving in cost of equipment. Also the return elbows 50 55 can now be made considerably smaller and therefore be covered with an ample thickness of insulation. Also the thickness of the heating walls proper can now be reduced in comparison to previously known arrangements. The common burner 25 may be completely omitted if 60 burners 26 are correspondingly increased in size or number.

A further simplification of the new arrangement is obtained, if the recirculation of the heating gases is not caused by a fan but through 65 the chimney action of the hot gases, produced in the interior of the heating walls proper. Such an arrangement is shown in Fig. 3.

The movable, hollow heating wall 1, which is 70 suspended on hangers 6 is in this case divided into four heating flues 52, 53, 54 and 55, by means of partition walls 48, 49 and 51. In each of the heating flues 52 and 54 two burners 56 75 have been placed at a medium elevation and at their lower ends, these burners receiving fuel

gas and air through pipes 57 and 58. In order to protect the fuel gas against the damaging influence of the hot heating gases, the fuel line 58 has been placed inside of the air line 57 in places where danger is greatest. The two air 5 conduits 51 of the two pairs of burners are connected to a header 59, which in turn is carried by two vertical pipes 61, 62, which connect to a cross main 63.

This cross main is led through narrow openings of hood 3 and is supported on one end by a sheave 64 and on the other end connected by means of a flexible tubing 65 to a distributing header 66 to which are also connected the corresponding cross mains 63 of the other heating walls. In a similar way the fuel gas pipe 67 emerging at the left end of cross main 63 is connected by flexible tubing 68 to a distributing gas header 69.

Distributing header 66 and gas header 69 are 20 fastened to a carriage 71, that can be moved a certain distance to the right jointly with the described system of gas and air pipes. Thus it is made possible to change the position of the burners 56 over to a position in flues 53 and 55, 25 whereby they pass through openings 72 of the partition walls 48 and 51.

The superfluous chimney gases escape through flue 73, one of which is attached to each of the heating walls, the flue having U-shape 74 and 30 passing through a water seal 75. In order to provide for a sufficient movability of the heating walls opening 76 in the enclosure 3, through which flue 73 must pass, has been made of ample size and has been sealed through a hood 77, which 35 projects over one leg of the U-shaped flue and dips down into the same water seal 75.

The sealing of the upper opening 5 of enclosure 3 is accomplished in the same manner as described in case of the first embodiment, namely 40 by filling gap 78 with a luting material, such as clay. In the same manner the coke chambers arranged between the heating walls are sealed during carbonization by means of covers, which are sealed by clay or the like. Closable openings 31 45 permit access to the burners in their various positions for purpose of ignition. The coal gas is led away from enclosure 3 through connections 42 into a collecting main 43.

After ignition of the burners 56 the heating 50 gases in the heating flues 52 and 54 rise upwardly as a result of the chimney action and descend in the heating flues 53 and 55 as a result of its diminished heat energy, caused by loss of heat to the heating walls, so that a permanent 55 revolving or recirculation is created as indicated by arrows 79. After burners 56 have been changed over to heating flues 53 and 55 the circulation of the heating gases takes place in opposite direction. The switching over of the 60 burners 56 by means of a motion of carriage 71 takes place in certain short intervals, similar to the reversing motion of damper plates 30 and 40 in the first embodiment. The switching over of the burner flames may also be accomplished 65 by a turning motion or by providing burners in each heating flue, whereby the burners would be used alternately.

In this embodiment have been avoided the entire recirculating equipment and the main gas 70 flues 16 and 17, the return elbows 15 and the connections 13 and therefore the embodiment compared to known apparatus is still more simplified, so that it can be used economically even for the smallest capacities.

I claim:—

1. In a coke oven of the class described a plurality of movable, internally heated heating walls, coke chambers formed between them, an enclosure surrounding said walls and adapted to collect the products of carbonization, heating flues in the walls, means for heating the heating gases contained in said flues, said means consisting of burners arranged inside of the heating walls, a fan adapted for circulation of the heating gases through the flues of the walls, said fan communicating with said flues in said walls by means of suction and discharge conduits and a chimney for off-flow of surplus heating gases from said wall communicating preferably with said discharge conduits.

2. In a coke oven of the class described a plurality of movable, internally heated heating walls, coke chambers formed between them, an enclosure surrounding said walls and adapted to collect the products of carbonization, heating flues in the walls, means for heating the heating gases contained in said flues, said means consisting of burners arranged inside of the heating walls, a fan, adapted for circulation of the heating gases through the flues of the walls, said fan communicating with each of said walls by means of suction and discharge conduits, an additional heating device outside of the enclosure common to all heating walls, said device preferably communicating with and discharging its combustion gases into said discharge conduits and a chimney adapted for releasing the surplus combustion gases, said chimney preferably communicating with said discharge conduits at a point between said heating device and said fan.

3. In a coke oven of the class described a plurality of movable, internally heated heating walls, coke chambers formed between them, an enclosure surrounding said walls and adapted to collect the products of carbonization, heating flues in the walls, means for heating the heating gases contained in said flues, said means consisting of burners arranged inside of the heating walls, said burners entering into the walls through

portions of the walls protruding through an opening provided in said enclosure and venting means adapted to release the surplus combustion gases from said walls and communicating with said walls.

4. In a coke oven, a plurality of hollow movable internally heated heating walls, coking chambers formed between said walls, an enclosure surrounding said walls and said chambers adapted to collect the products of carbonization from said chambers, means for heating the combustion gases contained in said walls by burners arranged inside of said walls, supply lines for supplying combustible gas and air to said burners said supply lines entering through portions of said walls protruding through said enclosure, conduits for carrying previously used heating gases to said walls and conduits for removing the surplus combustion gases and the previously used heating gases from said walls, all said conduits being hermetically sealed against contact with said products of carbonization.

5. In a coke oven, an enclosing chamber, surrounding a series of movable hollow internally gas-heated flued heating walls, and a series of coking chambers, sandwiched between said walls, means for re-heating the heating gases contained in said flues, said means consisting of gas burners arranged in said flues, supply lines for fuel gas and air to said burners, inlet conduits for carrying previously used combustion gases to said heating walls, outlet conduits for removing said previously used combustion gases and the surplus combustion gases from said burners from said walls, each of said coking chambers communicating with said enclosing chamber and the flues of each of said heating walls and the inlet and outlet conduits for combustion gases being closed to said enclosing chamber and a distillate gas offtake conduit communicating with said enclosing chamber for off-flow of distillate therefrom, separately from the hot combustion gas.
